Primary Examiner — Patricia Palasik

(57) CLAIM

The ornamental design for a perforating machine, as shown and described.

DESCRIPTION

FIG. 1 is a right side view of the perforating machine;
FIG. 2 is a front view of the perforating machine;
FIG. 3 is a top view of the perforating machine;
FIG. 4 is a bottom view of the perforating machine;
FIG. 5 is an upward-facing perspective view of the perforating machine; and,
FIG. 6 is a right bottom-facing perspective view of the perforating machine.
